UNITED STATES PATENT OFFICE.

THOMAS M. FRAEHLICH, OF ROUNDUP, MONTANA.

HAT-PIN.

No. 921,221.

Specification of Letters Patent.

Patented May 11, 1909.

Application filed November 30, 1908. Serial No. 465,127.

To all whom it may concern:

Be it known that I, THOMAS M. FRAEHLICH, a citizen of the United States, residing at Roundup, in the county of Fergus and 5 State of Montana, have invented new and useful Improvements in Hat-Pins, of which the following is a specification.

This invention relates to hat pins, designed especially for securing ladies' hats to 10 the hair of the head, the object of the invention being to provide a device of this kind which is simple of construction, convenient and effective in use, adapted to be readily and easily manipulated, capable of being applied to any ordinary type of hat, and 15 adapted to be manufactured and sold at a comparatively low cost.

The invention consists of the features of construction, combination and arrangement 20 of parts hereinafter fully described and claimed, reference being had to the accompanying drawing, in which:—

Figure 1 is a side elevation, partially in 25 longitudinal section, of a hat pin embodying my invention. Fig. 2 is a similar view, showing the sections of the pin open. Fig. 3 is a cross-section on line 3—3 of Fig. 2.

The pin comprises a pair of tubular rods or sections 1 and 2, each of which is threaded 30 at its outer end for the reception of an ornamental knob and finger piece 3. The section 1, which is relatively shorter than the section 2, is provided with a disk or attaching member 4 perforated for the passage of 35 fastenings to secure it to the side wall of the crown of the hat. Adjacent its inner end the said section 1 is provided with a depending lug or projection 5 having a pin receiving socket or opening 6, and serving as a 40 keeper member.

The section 2 carries a fastening pin 7, fixed at its outer end thereto, and projecting in parallel relation therewith toward the member 1, the free end of said pin being 45 adapted to enter the keeper opening 6 when the sections 1 and 2 are in closed relation to secure the hat upon the head. The inner end of the section 2 is provided with a perforation for the passage of the stem 8 projecting from the inner end of the section 1,

which stem is provided with a head 9 arranged to travel within the section 2. Surrounding the inclosed portion of the stem between this head and the inner end of the section 2 is a coil spring 10, which acts upon 55 the head to force it toward the outer end of said section 2, and to thus draw the two sections together in closed or locking position.

In practice, the member 1 extends through one side of the crown of the hat, while the 60 member 2 projects through the opposite side of the crown, the knobs or finger pieces being arranged upon the exterior for purposes of ornamental, as well as to enable the section 2 to be adjusted. The inclosed portion of the pin extends across the top of the crown above the head when the hat is in use, so that by drawing the section 2 outward to dispose the parts in the position shown in Fig. 2, the pin may be arranged 65 in position to engage the hair upon the head. After adjustment of the hat to the desired position, the operator releases the knob or finger piece 3 upon the stem 2, whereupon the spring 10 draws the section 2 inward, 70 thus forcing the fastening pin 7 through the hair and into the keeper opening 6 and securing the hat firmly upon the head. By simply drawing out upon the section 2 the fastening pin 7 may be retracted, leaving the 75 hat free to be removed.

Having thus fully described the invention, what is claimed as new is:—

1. A hat pin comprising two sections, a keeper upon one section, a fastening pin 85 upon the other section to engage said keeper, a telescopic connection between the sections, and a spring associated with said telescopic connection to draw the sections together.

2. A hat pin comprising two sections, one 90 provided with means for attachment to the hat, a keeper upon one of said sections, a fastening pin upon the other section to engage said keeper, a headed stem projecting from one section and entering the other section, 95 and a spring within the latter named section acting upon said stem and section to draw the sections together.

3. A hat pin comprising relatively fixed and movable sections, each of said sections 100

having a knob or finger piece at its outer end, the relatively fixed section also being provided with an attaching member, a keeper, and a headed stem, and the relatively 5 movable section having a tubular portion receiving said stem and a pin projecting parallel therewith to engage said keeper, and a spring within said tubular portion and

acting upon the same and stem to draw the sections together.

In testimony whereof I affix my signature in presence of two witnesses.

THOMAS M. FRAEHLICH.
